UNITED STATES PATENT OFFICE

116,862

DESIGN FOR A MILK BOTTLE

George N. Mas, Lynchburg, Va.

Application May 12, 1939, Serial No. 84,950

Term of patent 14 years

To all whom it may concern:

Be it known that I, George N. Mas, a citizen of the United States and residing at Lynchburg, Virginia, have invented a new, original, and ornamental Design for a Milk Bottle, of which the following is a specification, reference being had to the accompanying drawing, forming part thereof.

Fig. 1 is a front elevational view of the milk bottle, showing my new design.

Fig. 2 is a side view of the bottle shown in Fig. 1, and

Fig. 3 is a bottom plan view.

What I claim is:

The ornamental design for a milk bottle, as shown.

GEORGE N. MAS.
